UNITED STATES PATENT OFFICE

152,865

DESIGN FOR A WASHING MACHINE CASING

David Chapman, Chicago, Ill., and Arthur J. Wiltshire, Euclid, Ohio, assignors to The Apex Electrical Manufacturing Co., Cleveland, Ohio, a corporation of Ohio

Application June 12, 1947, Serial No. 139,606

Term of patent 14 years

(Cl. D49—1)

To all whom it may concern:

Be it known that we, David Chapman and Arthur J. Wiltshire, both citizens of the United States of America, residing, respectively, at Chicago, in the county of Cook and the State of Illinois; and at Euclid, in the county of Cuyahoga and State of Ohio, have invented a new, original, and ornamental Design for a Washing Machine Casing, of which the following is a specification, reference being had to the accompanying drawings, forming a part thereof in which

Fig. 1 is a front perspective view of a washing machine casing embodying our new design, and

Fig. 2 is a side perspective view of the washing machine casing shown in Figure 1. The rear of the casing (not shown) has an appearance substantially like the sides shown.

We claim:

The ornamental design for a washing machine casing, substantially as shown and described.

DAVID CHAPMAN.

ARTHUR J. WILTSIRE.
